UNITED STATES PATENT OFFICE.

HENRY C. HERR, OF DETROIT, MICHIGAN, ASSIGNOR, BY MESNE ASSIGNMENTS, TO
FIBER BARREL MACHINERY AND MANUFACTURING COMPANY, OF PITTSBURGH,
PENNSYLVANIA, A CORPORATION OF PENNSYLVANIA.

MACHINE FOR FORMING METAL HOOPS.

1,043,832.

Specification of Letters Patent. Patented Nov. 12, 1912.

Application filed February 19, 1910. Serial No. 544,879.

To all whom it may concern:

Be it known that I, HENRY C. HERR, a citizen of the United States of America, residing at Detroit, in the county of Wayne and State of Michigan, have invented certain new and useful Improvements in Machines for Forming Metal Hoops, of which the following is a specification, reference being had therein to the accompanying drawings.

The invention relates to machines for forming metal hoops, and has for its object the obtaining of a construction in which the hoop is both fashioned in cross section and curved longitudinally.

To this end, the invention consists in the construction as hereinafter set forth.

In the drawings—Figure 1 is a sectional elevation of the machine; Fig. 2 is a similar view looking at right angles to Fig. 1; Figs. 3 to 9 are sections showing the forming rolls which successively operate upon the work; and Fig. 10 is a view similar to Fig. 1, showing a modification.

In the manufacture of barrels, and particularly barrels in which the body portion is formed of paper, the heads are secured by metallic hoops. These hoops are so fashioned in cross section as to perform the function of croze and chime in the ordinary wooden barrel, as well as forming a reinforce for the paper body. It is therefore necessary in forming the hoops to fashion the metal to the proper section, and also to bend it longitudinally to the curve of the barrel body. These results are accomplished by a machine comprising a series of forming rolls for successively and progressively forming the section of the hoop, and arranged in such relation to each other that the metal in passing through the series is also curved longitudinally.

In detail, A is the frame of the machine, on which are mounted the forming rolls, and which in the construction shown in Figs. 1 and 2 is provided with a rotating wheel B, having its peripheral portion C fashioned to constitute a master die. The wheel is also provided adjacent to the portion C with a gear portion D, which is driven by engagement with a pinion E on a shaft F. This shaft in turn is driven through the intermeshing gears G and H from a drive pulley I sleeved upon a shaft J upon which the

wheel B is mounted. Around the peripheral portion of the frame are arranged a series of shafts K, K', etc., upon which are mounted the fashioning rolls L, L', etc. The latter are arranged in peripheral engagement with the master die C and are radially adjustable in relation by suitable means, such as the adjusting screws M. Certain of the rolls, such as L, L', are positively driven at the same peripheral speed as the master wheel through the medium of the pinions N, N' adjacent thereto which engage with the master gear wheel D.

The master die C is of the same cross section in all portions of its periphery, but the coöperating rolls L, L', etc., vary in form, and are designed to progressively affect the bending of the material into conformity with the master die. Furthermore, these rolls L, L', etc., in successively engaging with the hoop, will bend it longitudinally around the master die at the same time that it is being fashioned in section. The result is that at the completion of the cycle the metal will be bent into conformity to the section of the master die and into substantially the same curve, but the exact diameter of the circle in which the hoop is bent is dependent upon the adjustment of the rolls L, L' in relation to the master die. Thus by suitable adjustment, any diameter within certain limits may be obtained.

Figs. 3 to 9, inclusive, show the specific form of the successive rolls for forming the specific construction of hoop illustrated. The master die is provided with a cylindrical portion a, the outwardly-extending flange b at one end of the portion a, and at its opposite end the inwardly-extending inclined portion c, and the inclined portions d and e, the latter portions forming upon the strip the croze for receiving the head of the barrel. The first of the series of rolls L has the shoulder f coöperating with the outwardly-extending flange b on the master die to start the formation of a flange b'. This same roll has a portion g which bears upon the central portion of the hoop and assists in feeding the same. The second roll L' completes the formation of the flange b' and is provided with a flange h to hold the opposite edge of the hoop in position. The roll L² has an outwardly-projecting V-shaped portion i for starting the formation

2
of portion $c' d'$ of the hoop and these are completed by the roll L^3 , which also has a V-shaped portion j complementary to the V-shaped groove between the portions $c' d'$ of the master die. The succeeding rolls $L^4 L^5 L^6$ form the inclined portion e' of the hoop, and the last-mentioned roll has a portion l coöperating with a portion m on the master die for forming a slight return bend n in the hoop and for drawing the metal to remove all kinks or fullness therefrom.

It will be observed that the operations performed by the rolls above described gradually draw in the metal toward one side 15 of the hoop, and at the same time in passing around the master die and into engagement with the successive rolls the metal is bent longitudinally to the required curve.

In the construction illustrated in Fig. 10, 20 in place of the large wheel constituting the master die, a series of small rolls $P, P',$ etc., are arranged in a curved path, a part of said rolls being in proximity to and coöperating with the rolls $L, L',$ etc., while the intermediate rolls $P^2, P^3,$ etc., produce the longitudinal bending of the strip. With this construction, the rolls $P, P',$ etc., may be fashioned to progressively form the work, and the final roll of the series is of the form of 25 the fashioned strip. This construction is, however, more complex than the construction first described, and I deem the latter to be preferable.

What I claim as my invention is:

35 1. A machine for forming metal strips, comprising a master die and a series of forming rolls coöperating therewith to simultaneously shape the strip longitudinally and fashion it laterally throughout substantially the entire width thereof.

40 2. A machine for forming metal strips, comprising a rotary member having its peripheral portion provided with a work surface of the same contour or configuration throughout, and a series of forming members having working faces each corresponding to but a portion of the work surface and adapted to be brought sequentially into co-operation therewith to simultaneously shape 45 the strip longitudinally and fashion it laterally throughout substantially the entire width thereof.

3. A machine for forming metal strips, comprising a master die having a surface of 55 a configuration desired for the finished strip, and a series of forming rolls having peripheral working faces, said master die and said working faces being shaped to progressively fashion the edges and central portion of the strip laterally throughout substantially its entire width, the rolls being arranged in relation to the master die to progressively shape the strip longitudinally simultaneously with the lateral fashioning.

60 4. A machine for forming metal strips,

comprising a master die having a surface of a configuration desired for the finished strip, and a series of forming rolls each having peripheral working faces, said master die and said working faces being shaped to progressively fashion the strip laterally throughout substantially its entire width, said forming rolls being arranged in relation to the master die to progressively shape the strip longitudinally simultaneously with the lateral fashioning, and means for adjusting the forming rolls in relation to the master die for varying the longitudinal shaping of the strip.

5. A machine for forming metal strips, comprising a traveling master die having a uniform work surface provided with portions for fashioning the central portion of the strip laterally, a plurality of rolls each having a work surface corresponding to but 85 a portion of the work surface of the master die and adapted to be progressively brought into engagement therewith whereby the intermediate portion of the strip is progressively fashioned laterally, said rolls being 90 arranged in relation to the master die to progressively shape the strip longitudinally simultaneously with the lateral fashioning.

6. A machine for forming metal strips comprising a frame, a shaft journaled therein, a rotary member having its peripheral portion provided with a work surface of the same contour or configuration throughout and fashioned to constitute a master die, a series of forming rolls arranged about said 100 master die, each having working faces corresponding to but a part of said master die and adapted to be brought sequentially into co-operation therewith, the master die and the working faces of the rolls being shaped 105 to progressively fashion the edges and central portion of the strip laterally, shafts on which said forming rolls are mounted journaled in said frame, and means for adjusting said shafts to move said rolls radially 110 in relation to said master die.

7. In a machine for forming metal strips, the combination with a master die having a working surface of substantially the same contour and configuration throughout, and 115 a series of forming rolls each having a working face corresponding to but a portion of the master die surface, said rolls progressively coöperating with the master die to simultaneously longitudinally shape the strip 12 into hoop form and laterally fashion it to the shape desired for the function of croze and chime.

8. In a machine for forming metal strips, the combination with a rotary member having a working surface of substantially the same contour and configuration throughout and positioned to constitute a master die having flanged edge portions and intermediate inclined portions, and a series of rolls

- sequentially coöperating with said master die and having work faces corresponding to different portions thereof and adapted to progressively flange the edge and fashion the intermediate portions to the contour of the master die surface, said rolls being arranged in relation to the master die to shape the strip longitudinally into hoop form simultaneously with the lateral fashioning.
- 10 9. A machine for forming metal strips comprising a master die having a work surface of a configuration desired for the finished strip, and a series of forming members each having a surface corresponding to but a portion of such master die surface and 15 adapted to be brought sequentially into co-operation therewith to progressively fashion different lateral portions thereof and to simultaneously shape the strip longitudinally.
- In testimony whereof I affix my signature 20 in presence of two witnesses.
